 The Real Estate-Land Title and Trust Company, Philadelphia, Pa., a corporation of Pennsylvania

Application October 22, 1934, Serial No. 749,437

13 Claims. (Cl. 110—28)

This invention relates generally to fuel conveying and distributing apparatus for installation in furnace structures whereby to provide for the supply of fuel for combustion therein, and this application is a continuation in part of my application Serial No. 608,228, filed December 21, 1922 now Patent No. 1,977,620.

The principal objects and advantages of the present invention reside in the provision of an improved means for supplying solid fuel to a furnace fire box wherein the fuel is of a finely divided character, such for example as powdered coal, powdered coke, and the like, wherein the structure for delivering the fuel to the furnace serves as a distributing means as well as a grate structure; the provision of an improved grate structure wherein a solid fuel in a finely divided form may be introduced directly into the fire bed and distributed evenly throughout the same for combustion purposes; the provision of an improved grate structure for delivering a finely divided solid fuel to a furnace wherein the grate structure serves to convey the fuel to the fire box and as well distributes the fuel evenly while at the same time preventing clogging or caking of the fuel within the delivery means; the provision of an improved grate bar structure in which the powdered fuel may be delivered to a furnace, and in which the grate bar structure is self-cleaning, and also in one of its forms serves to break up clinkers or other obstructions which may form due to poor combustion or due to the poor quality of fuel; and the provision of an improved grate bar structure which may be conveniently installed in existing furnace fire boxes and which may be connected to a regulable source of supply which can be manipulated by an operator to maintain a substantially even fire within the fire box.

The foregoing, and such other objects and advantages as may appear as this description proceeds, are attained in structural embodiments of the invention as shown in the accompanying drawing, in which

Figure 1 is a fragmentary plan view partially in section of a furnace structure showing an assembly of the grate bars arranged for delivery of powdered fuel to the fire box thereof the grate bars being schematically represented in part.

Figure 2 is a schematic sectional view of a pair of the grate bar elements.

Figure 3 is a fragmentary sectional view of the grate structure of a modified form of the invention.

Figures 4 and 5 are, respectively, sectional

and fragmentary elevational views of one of the grate bars.

Figure 6 is a fragmentary sectional view taken along the line indicated by 6—6 on Figure 1.

Referring now more particularly to the drawing, I have illustrated one form of furnace structure incorporating improvements of my invention, Figure 1 showing a fire box 10 having side walls 11 and 12 and end walls not shown, which define the area of the fire.

Within the fire box 10 I provide a plurality of cylindrical, hollow, rotatable grate bars 15 which are arranged with their respective perimeters closely adjacent to each other and all substantially in the same plane, as will be seen from an inspection of Figure 2.

The grate bars are of a perforated nature, as will be described more particularly hereinafter, and are mounted for rotation in suitable bearings 11a and 12a at their respective ends.

At one end of each grate bar the grate bar itself fits into the bearing 11a while at the opposite end each grate bar is fixedly mounted upon a shaft 27 which fits into the bearings 12a and passes through the wall 12. The outer ends of the shafts 27 are provided with worm gears 16 which are in meshing engagement with a driving worm 17 which in turn can be driven by any convenient source of power.

At the ends of the grate bars adjacent to the bearings 11a, means are provided, as will be hereafter fully described, whereby fuel is introduced into the grate bars from the fuel inlet branches 18. These branches are in communication with a header 19 which receives powdered fuel from a suitable source of supply under pressure. In each of the branches 18, there may be provided a damper 20 which may be vertically adjustable for controlling a relative amount of powdered fuel admitted to each of the grate bars.

Inasmuch as the dampers 20 are outside of the furnace wall 11, they may be adjusted and maintained in the desired position by any convenient means. For example, as shown in Figure 6, one convenient means consists of a threaded bar 33 terminating at its lower end in a forked portion 34 and attached to the damper 20 by a pin 35. The upper end of the bar 33 passes through 36 and 37 in the spaced brackets 38 and 39 fastened to the wall of the furnace, and is engaged by a hand wheel 40, placed between the brackets, which is threaded to receive the bar 33 and provided with annular bearing portions 41 and 42 which respectively bear against the 55

lower surface of the bracket 38 and the upper surface of the bracket 39.

Thus an operator may regulate the quantity of fuel to be admitted throughout the furnace, thereby making uniform the fire throughout the fire box.

Referring now more particularly to the structure of the grate shown in Figure 1, it will be observed from Figure 2 that the grate bars 15 are substantially cylindrical and are provided with a plurality of radial perforations 21 throughout the full length of the exposed portion of the grate bars, to form a surface as shown in Figure 5, and which preferably take the form shown in detail in Figure 4. The perforations 21 are of the general tapering form from the interior of the grate bar toward the outer cylindrical surface thereof, but are terminated short of the outer surface as indicated at 22, and then countersunk as indicated at 23 to form a circumferential series of edge portions 24, which are exposed in the form of the invention shown in Figure 1 to the interior space of the fire box.

As these grate bars are rotated and the finely divided solid fuel is ejected therefrom, the fuel is consumed in the furnace. Should any clinkers form and drop upon the grate bar these clinkers come in contact with the edge portions 24, and are either broken up or are reduced to such size as to either fall between the respective grate bars or become consumed in the fire.

Inside of each of the grate bars I provide a cylindrical member 25 which fits the internal surface of the grate bar and extends from the grate bar at one end to abut and communicate with the inlet 18 thus affording a conduit for carrying the powdered fuel into the grate bar. This member 25 is retained in a stationary position by any convenient means acting upon the end which extends from the grate bar so that the grate bar 15 rotates about the member 25. The upper sector of that portion of the member 25 which is within the grate bar 15 is cut away to form a longitudinal slot 26, as best shown in Figures 2 and 4. Thus, when the grate bar 15 is rotated about the member 25 the openings 21 of the grate bar are successively presented to the opening 26 and the powdered fuel under pressure is ejected through the openings of the grate bar. In view of the constricted form of the openings, approaching the shape of a Venturi tube, a spraying effect is given to the fuel as it is ejected from said openings, thus distributing the same in a cloud within the furnace fire box so that it is readily consumed therein.

The shaft 27 extends axially within the grate bar, as shown in Figure 4, and this shaft may be provided with a series of triangular enlargements 28 which are adapted to rotate with the shaft within the trough 25, thus cooperating with the trough to remove any fuel which may become caked or packed therein. Thus the fuel is constantly ejected from within the grate bar and does not become clogged, and thereby any blocking of the trough member due to the caking of the fuel is effectually eliminated.

In the alternative form of the invention shown in Figure 3, the general operative structure is similar to that shown in Figures 1, 2 and 4, but inasmuch as the furnace bed may for some purposes be provided with a fire brick bottom, the grate bars 15a, as shown in Figure 3, are mounted within protective cylindrical casings 29, which are provided with apertures 30 registering with

complemental apertures 31 in the fire brick sections 32.

The forms of the invention shown in Figures 1, 2 and 3 are similar in that the fuel is allowed to escape in a cloud from the grate bars themselves, which serve as conductors for the fuel from the header to desired points within the furnace structure. In the form of the invention shown in Figure 2, where the grate bar is exposed to the interior of the fire box, the trough 10 is provided for controlling the discharge of the fuel through the apertures 21. Similarly to the control by the trough 25, the shields 29 shown in Figure 3 serve to control the point of discharge of the powdered fuel into the furnace.

The elements 28 shown in Figure 4, may likewise be provided in the grate bar shown in Figure 3 as indicated so that in both of the forms of the invention shown, clogging of the grate bar due to caking of the fuel supply is effectually prevented.

Having thus described my invention and illustrated its use, what I claim as new and desire to secure by Letters Patent is:

1. In a furnace, in combination, a fire box, and means for injecting comminuted fuel in suspension into said fire box at a plurality of separate points, said injecting means including a plurality of distributing units each comprising two substantially cylindrical concentric tubes, one of said tubes being mounted for rotation relative to the other, and means for continuously rotating said rotatable tubes, said tubes having apertures which periodically register when said rotatable tube is rotated.

2. In a furnace, in combination, a fire box and a grate structure comprising a plurality of units which support and are overlaid by blocks of refractory material having perforations therein, said units each comprising a cylindrical casing 40 having an aperture which registers with the apertures in said refractory blocks, and a cylindrical member having a plurality of radial perforations and rotatably mounted within said casing, means for introducing fuel in suspension into the fire 45 box through said cylindrical members and means for continuously rotating said cylindrical members whereby the fuel is continuously agitated and the perforations in said cylindrical members periodically register with the apertures in said 50 casings and refractory blocks.

3. In a furnace in combination with a firebox of a grate structure including a hollow cylindrical member mounted for rotation having a plurality of apertures therethrough, means for rotating said member, means for supplying finely divided solid fuel to the interior of said member for transmission through said apertures for combustion, stationary means cooperating with the inside surface of said member for regulating the active area of said member, and means for preventing clogging of fuel within said member.

4. In a furnace in combination with a firebox, a grate structure comprising a plurality of hollow cylindrical grate members having a plurality of apertures in the walls thereof and mounted for rotation and in parallel relationship adjacent each other, means for feeding finely divided solid fuel to the interior of each grate member for transmission through said apertures, means for controlling the direction of the passage of the fuel through said apertures, means for controlling the quantity of fuel passing through each grate and means for rotating said grate members si- 75

multaneously in the same direction during combustion of said fuel.

5. In a furnace in combination, a grate structure comprising a plurality of rotatable hollow cylindrical grate bars, each of said grate bars having a plurality of apertures therethrough, means for supporting said grate bars in parallel adjacent relationship, means for rotating said grate bars, a refractory wall disposed over said series of grate bars, said wall having a perforation above the length of each grate bar and registering with a series of apertures in each grate bar as it rotates, means for delivering finely divided solid fuel in the interior of each grate bar and means for confining the discharge of fuel through each grate bar to the apertures in the grate bar registering with the apertures in the refractory wall.

6. In a furnace in combination with a firebox, 20 a grate structure comprising a plurality of rotatable hollow perforated grate bars, means for supporting said bars in parallel relationship, a wall of refractory material disposed above said series of grate bars, said wall having perforations 25 along one portion of each grate bar, means for delivering finely divided solid fuel into the interior of each grate bar, means for restricting the discharge of fuel to the apertures of each bar registering with the apertures in said refractory 30 wall as said bar rotates, means for rotating each grate bar and means for preventing the clogging of fuel within each grate bar.

7. In a furnace in combination with a firebox, a plurality of hollow cylindrical grate bars, each 35 grate bar having a plurality of Venturi apertures therethrough, means for mounting said grate bars for rotation and in close parallel relationship, means for rotating said grate bars, means for delivering finely divided solid fuel to the interior of each grate bar for transmission through said apertures and means on each grate bar for controlling the active area of the grate bar.

8. In a furnace in combination with a firebox, 40 a plurality of hollow cylindrical grate bars having a substantial wall thickness, each grate bar having a plurality of Venturi apertures therethrough, the number of said apertures and said wall thickness being so related that the outer grate surface is composed of abrading edges, 45 means for mounting said grate bars in close parallel relationship, means for revolving said grate bars simultaneously and in the same direction during combustion, means for delivering finely divided solid fuel to the interior of each grate 50 bar for transmission through said apertures, a split cylindrical member disposed on the inside of each grate bar, and means for maintaining said split members stationary, whereby an active grate surface is continuously presented at the 55 top of each grate bar.

9. In a furnace in combination with a fire box, 5 a grate structure comprising a plurality of hollow cylindrical grate bars mounted for rotation and disposed in parallel relation, each grate bar having a plurality of apertures, means for delivering to the interior of each grate bar solid fuel in finely divided form and forcing said fuel through said apertures for combustion, means for controlling the direction of the flow of said fuel through said apertures and means for rotating said grate bars.

10. In a furnace structure, in combination, a 10 grate structure including a rotatable hollow cylindrical grate bar having a plurality of peripheral apertures, means for delivering solid fuel in finely divided form to the interior of said grate and forcing said fuel out through said apertures, 15 means associated with said grate bar for controlling the flow of the fuel through said apertures, and means for rotating said grate bar.

11. In a furnace structure, in combination, a 20 grate structure including a rotatable hollow cylindrical grate bar having a plurality of peripheral apertures, means for delivering solid fuel in finely divided form to the interior of said grate and forcing said fuel out through said apertures, 25 means associated with said grate bar for controlling the flow of the fuel through said apertures, means for rotating said grate bar, and means within the grate bars for preventing the 30 clogging of the fuel therein.

12. In a furnace structure, in combination, a 35 grate structure comprising a plurality of hollow cylindrical grate bars mounted for rotation and disposed in parallel relationship adjacent to each other, each grate bar having a plurality of apertures, means for delivering solid fuel in finely divided form to the interior of each grate bar and discharging said fuel through said apertures for combustion, means for controlling the supply 40 of fuel to each grate bar, means for controlling the direction of discharge of the fuel through said apertures, and means for rotating said grate bars during combustion.

13. In a furnace in combination a grate structure 45 comprising a plurality of hollow cylindrical grate bars having a plurality of peripheral apertures through the walls thereof, the outer portions of said apertures flaring to form abrading ridges on the outer surfaces of said grate bars, 50 and said grate bars being mounted for rotation, means for rotating said grate bars, means for delivering finely comminuted solid fuel to the interior of said grate bars and discharging said fuel through said apertures and means to cause 55 said fuel to be discharged only through the apertures in the upper surfaces of said bars as they rotate.
